ATTORNEY.

UNITED STATES PATENT OFFICE

159,867

SUN VISOR

Jules F. Saut, Detroit, Mich., assignor to Reynolds Metals Company, Richmond, Va., a corporation of Delaware

Application December 8, 1949, Serial No. 6,504

Term of patent 7 years

(Cl. D14—6)

To all whom it may concern:

Be it known that I, Jules F. Saut, a citizen of the United States, residing in Detroit, county of Wayne, and State of Michigan, have invented a new, original, and ornamental Design for Sun Visor, of which the following is a specification, reference being had to the accompanying drawing, forming part thereof.

Fig. 1 is a top plan view of a sun visor, showing my design, and

Fig. 2 is an end elevation thereof.

I claim:

The ornamental design for a sun visor, as shown.

JULES F. SAUT.
